DOWN INDICATOR FOR FOOTBALL GAMES
WITH CROSS-SHAPED ROTOR AND T-
SHAPED CASE

Myron R. Schall, Sacramento, Calif.

Application January 19, 1946, Serial No. 642,200

5 Claims. (Cl. 40—70)

1

This invention relates to, and it is an object to provide, a novel indicating device for use at football games to indicate to the players and spectators alike the "down" in any given series of plays; such down indicator being intended for use by the head linesman and in place of the box-like indications now commonly in use.

Another object of the invention is to provide a down indicator which is readily visible, relatively light-weight, easy to manipulate and operate, and of durable construction.

A further object of the invention is to provide a down indicator which is adjustable as to height, whereby the head linesman can adjust the device so that the down indicating portion thereof is above his head for ready visibility.

An additional object of the invention is to mount the down indicating portion of the device for rotation about a vertical axis so that such portion may be rotated, on each down, so that spectators at the ends as well as at the sides of the playing field may view the down indication.

A further object of the invention is to provide a simple and inexpensive device and yet one which will be exceedingly effective for the purpose for which it is designed.

These objects are accomplished by means of such structure and relative arrangement of parts as will fully appear by a perusal of the following specification and claims.

In the drawings:

Figure 1 is an elevation of the down indicator as in use.

Figure 2 is a similar view, but with the adjacent side plate of the T-shaped case broken away, and with the standard removed.

Figure 3 is an end elevation of the device, with the standard removed.

Figure 4 is an enlarged fragmentary sectional elevation of the detachable coupling means between the down indicating portion of the device and the vertically adjustable standard.

Figure 5 is a cross section on line 5—5 of Fig. 1.

Referring now more particularly to the characters of reference on the drawings, the device comprises a flat, cross-shaped rotor 1 formed of light weight material, such as hard fibreboard or the like; such rotor including legs 2 curved at their outer ends in concentric relation to the axis of rotation. The legs 2 are numbered from "one" to "four," as shown, with said numbers appearing in identical relation on opposite sides of the rotor; this numbering representing the downs in each series of play in the game of football.

The cross-shaped rotor 2 is turnably mounted

2

in a relatively thin T-shaped case, indicated generally at 3, which case includes laterally projecting legs 4 and a downwardly projecting leg 5. The T-shaped case 3 includes adjacent but spaced side plates 6 which form the legs 4 and 5, and which plates are connected, at the outer ends of said legs, as at 7.

The rotor 2 is disposed between the side plates 6 in spaced relation thereto, and is turnably supported on a central pivot bolt 8 for rotation within the case 3. The size and configuration of the rotor 2 is such that when one of the legs 2 of the rotor projects vertically upwardly, the remaining legs of said rotor lie in symmetrical, covered relation by the legs 4 and 5 of the T-shaped case 3. Said case is notched or cut away at its upper edge and centrally thereof, as at 9, so as to expose the whole of the rotor leg 2 which is in upstanding position.

In order to support the rotor 2 against wobbling it is provided at the center portion thereof, and on opposite sides, with spacer discs 10 which are affixed thereto, and which discs engage the inner faces of the side plates 6 with an easy running fit.

One of the spacer discs 10 is fitted, on the outside, with a filler disc 11 of reduced diameter, which runs in a matching opening in the adjacent side plate 6. A handle 12, which includes a circular base 13, is secured to one end of the pivot bolt 8 exteriorly of the case 3, with said base 13 abutting the filler disc 11. Pins 14 extend from the circular base 13 of the handle into the assembly of the filler disc 11 and adjacent spacer disc 10. It will be seen that by reason of the above arrangement, rotation of the handle 12 will cause similar movement of the rotor 2 within the case 3.

The device includes a telescopic, vertically adjustable standard 15 detachably coupled, at its upper end, to the lower end of the downwardly projecting leg 5 of the case 3, as follows:

A spindle 16 is turnably mounted in the upper end of the standard 15 and includes an enlarged radial collar 17 intermediate its ends which engages in rotatable relation in a seat 18 formed in the upper end of said standard. The spindle 16 projects above the enlarged radial collar 17 into a socket 19 formed on the lower end of an upwardly projecting yoke 20 which straddles, and is affixed to, said downwardly projecting leg 5 of the case. The upper end portion of the spindle 16 is releasably secured in the socket 19 by a set screw 21.

When the device is assembled and is being prepared for use, the standard 15 is adjusted to

proper height by the head linesman, and so that the down indicating portion of the device is readily visible above his head.

During each series of play, the head linesman manipulates the handle 12 so that the leg 2 which bears the correct indication of the down projects upwardly from the case for viewing, which viewing is facilitated by the cut-a-way portion 9 of said case.

The device is of substantial size so that the down indication may be readily seen by both the players and the spectators. As the rotor is changed from one position to another, to indicate a change of downs, the head linesman may rotate the case 3 with the spindle 16 as an axis of rotation, whereby spectators beyond the ends of the playing field, as well as those along the sides of the playing field, may obtain a view of the down indication. When the play takes place the case is of course disposed so that one side faces the playing field.

When the device is not in use the set screw 21 is loosened and the spindle 16 removed from the socket 19, whereby to facilitate carrying of the parts of the device from place to place.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent are desired:

1. A "down" indicator for football games comprising a flat, cross-shaped rotor having legs of equal length, like "down" indicia on each leg on opposite faces thereof, a flat, relatively thin T-shaped case including adjacent but spaced T-shaped side plates connected together at the ends of the legs thereof, the rotor being pivoted in the case for rotation about a central axis, the case being symmetrical to the rotor and enclosing the remainder thereof when one leg of said rotor projects upwardly above said case, and a standard on which the case is secured in supported relation.

2. A "down" indicator for football games comprising a flat, cross-shaped rotor having legs of equal length, like "down" indicia on each leg on opposite faces thereof, a flat, relatively thin T-shaped case including adjacent but spaced T-shaped side plates connected together at the ends of the legs thereof, the rotor being pivoted in the case for rotation about a central axis, the case

being symmetrical to the rotor and enclosing the remainder thereof when one leg of said rotor projects upwardly above said case, and a standard on which the case is secured in supported relation; said last named means including an upwardly standing spindle turnably supported on the standard, and a socket member on the case at the bottom; the spindle being releasably secured in the socket member.

3. A "down" indicator for football games comprising a flat, cross-shaped rotor having legs of equal length, like "down" indicia on each leg on opposite faces thereof, a flat, relatively thin T-shaped case including adjacent but spaced T-shaped side plates connected together at the ends of the legs thereof, the rotor being pivoted in the case for rotation about a central axis, the case being symmetrical to the rotor and enclosing the remainder thereof when one leg of said rotor projects upwardly above said case, and a standard on which the case is secured in supported relation; there being a handle mounted exteriorly of the case operative to rotatably adjust said rotor.

4. A "down" indicator for football games comprising a case consisting of a pair of relatively thin spaced apart matching plates, such plates having relatively straight top edges and the case being open adjacent said top edges and the plates being secured together adjacent the other edges thereof, a relatively thin flat rotatable element journaled between the plates and being of such a size that a substantial portion thereof projects above the straight edges of the plates as such element is rotated, like "down" indicating numbers disposed in matching relation on each flat face of the element, the numbers being arranged at substantially right angles to each other on the element whereby with each quarter turn given such element one number will be exposed above the top edges of the case.

5. A "down" indicator as in claim 4 including a standard, the case having its flat faces vertically disposed, and such case being journaled on said standard for free turning movement about the longitudinal axis of the standard.
